INVENTOR
JOHN ARSENEAU

UNITED STATES PATENT OFFICE.

JOHN ARSENEAU, OF SHEDIAC, NEW BRUNSWICK, CANADA.

CLOTHES AND LINE GRIP.

1,355,376.

Specification of Letters Patent. Patented Oct. 12, 1920.

Application filed January 13, 1920. Serial No. 351,204.

To all whom it may concern:

Be it known that I, JOHN ARSENEAU, a subject of the King of Great Britain, and resident of the town of Shedia, in the Province of New Brunswick, in the Dominion of Canada, have invented certain new and useful Improvements in Clothes and Line Grips, of which the following is a specification.

10 This invention relates to improvements in pins, designed for hanging clothes, either on a rope, in rooms, presses, or for holding office papers and files, and the objects of the invention are to facilitate securing an article to be hung between the jaws of the pin, and thus suspending the pin from a suspending means such as a rope, cord, or the like, to simplify the arrangement of the several parts of the pin, and better adapt it 20 to perform the functions required of it.

With the above and other objects in view, the invention consists essentially of the improved construction, particularly described and set forth in the following specification 25 and accompanying drawings forming part of the same.

In the drawings:—

Figure 1 is a perspective view of the improved pin as seen when hanging clothes 30 from a line.

Fig. 2 is a side elevation of the same.

Fig. 3 is a front elevation of the improved pin.

Fig. 4 is a front elevation of one member 35 of the pin.

Fig. 5 is a front elevation of the second member of the pin.

Fig. 6 is a fragmentary side elevation of 40 the upper end of the two members of the pin, showing the method of securing the same together.

Like characters of reference refer to like parts in the several figures.

Referring to the drawings, A represents 45 a pin, consisting of two members, B and C, hingedly connected together.

The member B is formed of a piece of resilient wire, which is bent in U-shape, and is provided with a curl 10, after which the 50 piece of wire is bent substantially rectangular to form a jaw 11.

The wire is then bent to form a second curl or eyelet 12, which is arranged in alignment with the eyelet 10, and the free ends 55 of the wire are then secured together as shown at 13.

The second member C is formed of a piece of resilient wire, and is bent to form a shank 14 from which a laterally extending U-shaped projection 15 is formed, and the 60 wire is then bent to form a jaw 16.

The wire is now bent to form a second lateral projection 17, in alignment with the projection 15, and the shank is completed by securing the end 18 of the wire to the 65 other portion of the shank.

In this case, one end of the wire is formed with an upwardly extending projecting end 19 having a lateral angularly disposed hook member 20.

70 The projections 15 and 17 engage with the rings or eyelets 10 and 12, and the offset hook end 20 of the member C is designed to pass through the upper U-shaped end of the member B, the jaws 11 and 16 being designed 75 to engage. The members B and C are under tension when in a closed position, this being effected by offsetting the jaws 11 and 16 as shown in Fig. 2.

It will thus be seen that the two members 80 B and C are hingedly connected and may be opened, and clothes will be embraced between the jaws 11 and 16 of the pin A.

The jaws are then closed by rotating the shank 16 toward the upper portion of the 85 member B, and passing the offset hook end 20 through the U-shaped upper portion of the member B.

It should be particularly noticed that 90 when the hook end 20 is released from pressure, it will engage with one of the side arms of the member B, and so hold the clothes in position, this engagement of the hook-shaped end 20 being shown in Fig. 6.

When suspending the clothes from a line, 95 it is only necessary to press the upper ends of the two members B and C together to disengage the hook end 20 of the member C from the member B, and the said hook end will then be made to embrace the line 100 as shown in Fig. 1.

This pin cannot be displaced laterally, or any other way, and there is no possibility of it working loose from the line, or from the clothes working loose from the jaws of 105 the pin.

This pin may also be utilized in offices for hanging files, and for many other purposes, in which an article is to be suspended from a hanging member.

As many changes could be made in the 110 above construction, and many apparently

widely different embodiments of my invention, within the scope of the claim, constructed without departing from the spirit or scope thereof, it is intended that all matter contained in the accompanying specification and drawings, shall be interpreted as illustrative and not in a limiting sense.

What I claim as my invention is:—

A pin comprising a pair of members, one 10 of the members having loops formed in the side walls, the other member having lateral projections adapted to engage the loops, whereby the members are pivotally connected, the said members being formed with

jaws, one of the members being provided 15 with an offset end terminating in a hook projection adapted to pass through and engage one arm of the other member, and also to be engaged by a flexible supporting member, whereby the said supporting member 20 is clamped between the two members constituting the pin.

In witness whereof I have hereunto set my hand in the presence of two witnesses.

JOHN ARSENEAU.

Witnesses:

AGNES O'ROURKE,

W. B. CONNOLLY.
